(57) **CLAIM**

The ornamental design for a battery box, as shown and described.

DESCRIPTION

FIG. 1 is a side view of the battery box, showing my new design.

FIG. 2 is a side view thereof, rotated 180° about a vertical axis from that shown in FIG. 1.

FIG. 3 is a bottom plan view thereof.

FIG. 4 is a top plan view thereof.

FIG. 5 is an end view taken from the left side of FIG. 3; and, FIG. 6 is an end view rotated 180° about a vertical axis from that shown in FIG. 5.
